E. A. CORBIN, JR

CONDIMENT HOLDER OR SALT SHAKER

Filed May 10, 1923

INVENTOR:

Elbert A. Corbin, Jr.
BY
Wiederholt & Gimbault.

ATTORNEYS.

UNITED STATES PATENT OFFICE.

ELBERT A. CORBIN, JR., OF SWARTHMORE, PENNSYLVANIA.

CONDIMENT HOLDER OR SALT SHAKER.

Application filed May 10, 1923. Serial No. 637,988.

To all whom it may concern:

Be it known that I, ELBERT A. CORBIN, Jr., a citizen of the United States, residing at Swarthmore, in the county of Delaware and State of Pennsylvania, have invented a new and useful Condiment Holder or Salt Shaker, of which the following is a specification.

My invention relates to the general class 10 of condiment holders or containers applicable in particular to containing and dispensing granular or powdered substances, such as salt, pepper, spices, sugar and similar articles that are intended for household use, and have to be protected from dampness, dust or other extraneous matter, and the contents of which unless frequently shaken up are apt to become compacted and in consequence are not easily shaken out.

20 The principal object of my invention is the construction of a container for granular or powdered substances or the like which embodies a body having a valved outlet and a cover construction formed with a recess to guide the valve stem the contents of the container being protected from the atmosphere, water or other liquids and from ants and other insects.

To the above ends my invention consists 30 of a novel and useful container applicable to salt, pepper, spices, granulated and powdered sugar and all other powders that are used frequently and that have to be scattered in use, and that must be protected 35 from dampness, dust or other extraneous matter.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged 45 and organized and that my invention is not limited to the precise arrangement and organization of these instrumentalities as herein shown and described.

Figure 1 represents a vertical sectional view of a condiment holder or container, embodying my invention, the section being taken on line 1—1 Figure 2.

Figure 2 represents a section on line 2—2 Figure 1.

55 Figure 3 represents a side elevation of a modified form of the valvular member.

Figure 4 represents an end view of Figure 3.

Figure 5 represents a sectional view of the cap of a modification.

Figure 6 represents a sectional view of the body of said modification.

Figure 7 represents a perspective view of the outer skeleton frame of said modification.

Similar numerals of reference indicate corresponding parts.

Referring to the drawings:

1 designates my novel construction of salt shaker or condiment holder, the same comprising the body 2 having the salt receiving chamber 3, whose bottom wall converges inwardly as at 4, and has the throat, valve seat or outlet opening 5, terminating in the flaring mouth 6, whose bottom surface 7 forms a base for the shaker on which it normally rests. The upper portion of the body 2 is exteriorly screw threaded as at 8, and is engaged by the interiorly screw threaded wall 9 of the cap 10, which is composed of the upper wall 11, and the central hollow boss 12 having the hollow guide recess 13 in which is received the upper end 14 of the valve stem 15, which projects upwardly from the valve 16, whose lower shoulder or edge 17 performs the valvular function proper and normally rests on the lower portion of the concaved wall 4, slightly above the throat or valve seat 5.

18 designates pendant vanes or wings, which depend from the valve shoulder 17 and pass through the opening or throat 5 and terminate in the bottom head or disc 19.

It will be seen from the foregoing that the length of the valve stem is somewhat greater than the distance between the top of the valve seat at about the point 5, and the bottom of the recess 13, so that the upper portion of the valve stem is always contained within the recess 13, while the lower portion of the valvular member is effectively guided by the wings or vanes 18, the contents of the container having their exit between said vanes and around the disk or bottom 19, which may be omitted, if desired.

The operation is as follows:

To use my novel device, it is only necessary to shake it up and down gently, the reciprocations up and down serving to unseat the valve to the desired extent and

permit the requisite quantity of salt or other condiment to be dispensed.

As a salt shaker my novel device has advantages over the conventional type, in that its valvular action keeps the salt protected from the atmosphere and the cover construction makes it proof against moisture or water or other liquids being spilled over it. Vermin such as ants or small flies cannot 10 enter the receptacle. Most salt shakers of the conventional type get clogged in damp weather on account of the many small apertures through which the salt must flow, while in my device the salt flows by gravity 15 through a circular opening in the bottom of the container through the throat 5, and this charge of salt is spread outwardly by the disc 19 at the extreme lower end of the valve head or plunger 16. The plunger 16 acts in 20 a threefold capacity, first, as a valve at its bottom edge 17, second as an agitator for the contents of the container at the shoulder above this edge and third as a spreader at the disc 19. The top end of the stem 15 is 25 guided in the small open ended recess 13, while the bottom end of the valvular member is guided in the hole or throat 5 at the bottom of the container by the plurality of vanes or wings 18. In filling with fresh 30 salt the cover 10 may be unscrewed and the valve 16 left in place at its lower end, or the container may be turned upside down with the cover screwed on and filled from the bottom with less effort. To clean, the 35 cover can be removed and the plunger or valvular member withdrawn and all three parts cleaned separately.

My novel design of powder distributor will function very satisfactorily when used 40 with powdered or pulverized sugar, flour and the like, as these very fine powders have a tendency to bridge across and clog up even moderately large holes in the conventional shaker cap.

45 It will be apparent that my novel condiment holder has only three parts, which are quickly and easily disassembled for cleaning. Furthermore, my novel device can also be refilled without removing the cover, which is 50 a great time saver in large hotels and restaurants, and since it seldom has to be taken apart and is always closed when not in use, it is more sanitary than other types.

55 My novel construction further enables the user to release only a small charge of condiment with a slight shake of the container and a larger charge of condiment with a greater agitation of the container. In other words, my novel device responds automatically 60 to the degree of agitation supplied by the user and the flow responds to each agitation and has no opportunity to bridge across or block up the exit at any time, even in damp weather.

65 Since my novel device has an automatic

plunger valve seated by gravity, it does not have to be inverted to release its contents nor to be mechanically operated like other bottom vented containers now in use. These bottom vented mechanically operated containers have from 6 to 9 parts, some of which are made of corrosive metal, while my device is made preferably of glass with only three pieces which are easy to demount or dismantle and clean, and further this glass construction shows the user, the different contents at a glance and signals when the container is empty. Salt, black pepper, paprika and red pepper or any other contents of the container can be immediately 70 distinguished from each other.

In the construction seen in Figs. 1 and 2, it will be apparent that the salt or other material in its exit from the container falls upon the curved walls 20 and thence over 75 the outer periphery of the disk 19. If desired I may omit the concave walls 20 and the bottom disk 19 and construct the valvular member, as seen at 21 in Fig. 3, all the parts 14, 15, 16 and 17 being substantially 80 the same as seen in Fig. 1. The vanes or wings 22 however, are made without the curved walls 20 and the disk 19 is also dispensed with, so that the material after passing 85 the edge 17 can flow in straight lines past or along the vanes 22. While I have shown 3 vanes or wings 22 as being employed in Figs. 1 to 4 it will be evident that 90 the number of vanes or wings 22, may be increased or diminished according to requirements.

In Figs. 5, 6 and 7 I have shown another embodiment of my invention which may be employed when it is desired, to make a more expensive or ornate container, certain of the 95 parts as the cap seen in Fig. 5 and the skeleton frame seen in Fig. 7 being made of metal, as gold, silver, aluminum or the like, which can be chased or ornamented with any desired configurations.

In assembling the structures seen in Figs. 5, 6, and 7 it will be apparent that the glass body 23 can be dropped within the skeleton frame 24, the lower end 25 of the body 23 105 having the throat or outlet 26 resting upon the shoulder 27 of the frame 24, while the upper end of the body 23 terminates in proximity to the exteriorly threaded ring 28.

110 The valvular member as 21 is next dropped into the body 23 and the cap 29 is screwed upon the ring 28. The inverted cup member 30 performs the same function 115 as the recess 13 and receives the upper end of the valve stem, when the parts are assembled, as is evident.

120 The parts seen in Figs. 5, 6 and 7 now being assembled, it will be apparent that the valve of the member 21 seen in Fig. 6 125 will function in the manner which has already been described.

The skeleton frame seen in Fig. 7 is composed of the upper and lower annular members 28 and 27, joined by the upright bars 31, bent inwardly at their lower ends below which is a base 32. Other forms of this skeleton frame may be designed or employed for the purpose stated. The cup member 29 seen in Fig. 5 can be composed of one or two members as may be desired, the structure seen in Fig. 5 being composed of the inverted cup shaped member 30, brazed, spot welded or otherwise secured to the top 33 in any suitable manner, or if desired the inverted cup member 30 can be formed by pressing or stamping integral with the top 33.

It will now be apparent that I have devised a new and useful condiment holder or salt shaker, which embodies the features of advantage enumerated as desirable in the statement of the invention and the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what I claim as new and desire to secure by Letters Patent, is:—

1. A condiment holder, comprising a body, a top therefor having a central recess therein open at its bottom, a gravity seated valve contained in said body and having a pendant wing extending through the lower opening of said body, to guide the lower portion of said valve, and a valve stem for said valve having its upper end extending into the recess in said cap, whereby the upper and lower portions of said valve are always centrally positioned and guided with respect to said body.

2. A condiment holder, comprising a body portion open at both ends, the lower opening forming a valve seat, a closed cap for said body having a centrally located recess therein open at its bottom, and a valve stem contained in said body and having its upper end positioned in said central recess and its lower end enlarged and forming a valve, whose top flares outwardly and downwardly at its junction with said stem, and wings depending from said valve and passing through the valve seat, the inner walls of the lower portion of said body above said valve seat converging inwardly towards said

seat, and the length of said stem being greater than the distance from the top of said valve seat to the bottom of the recess in said cap.

3. A condiment holder, comprising a body portion open at both ends, the lower opening being a throat extending through the base of said body and forming a valve seat, a closed cap for said body having a centrally located recess therein, open at its bottom, and a valve stem contained in said body and having its upper end positioned in said central recess and its lower end enlarged and forming a valve, whose top flares outwardly at its junction with said stem, and wings depending from said valve, the inner walls of the lower portion of said body above said valve seat converging inwardly towards said seat, and the length of said stem being greater than the distance from the top of said valve seat to the bottom of the recess in said cap, said wings projecting through said valve seat and serving as a guide to the valvular member, the latter seating by gravity upon the lower inner converging inner walls of said body above said throat.

4. A condiment holder comprising a body portion open at both ends, the lower opening forming a valve seat, a closed cap for said body having a centrally located recess therein open at its bottom, and a valve stem contained in said body and having its upper end positioned at all times in said central recess and its lower end forming a valve, whose top flares outwardly at its junction with said stem, wings depending from said valve, the inner walls of the lower portion of said body above said valve seat, converging inwardly towards said seat, and the length of said stem being greater than the distance from the top of said valve seat to the bottom of the recess in said cap, said wings projecting through said valve seat and serving as a guide for the valvular member, and a bottom disk for said wings over the outer edges of which the material is dispensed.

5. A condiment holder, comprising a body open at both ends, a skeleton frame enclosing said body, a cap at the upper portion of said body and having a central recess therein open at its bottom, a valve for the lower portion of said body, and a valve stem for said valve having its upper end at all times positioned within the recess in said cap.
